US0D1034835S

(12) United States Design Patent (10) Patent No.: US D1,034,835 S
(45) Date of Patent: * Jul. 9, 2024

(54) TOY MAKEUP BOX

(71) Applicant: Mingkai Chen, Shantou (CN)

(72) Inventor: Mingkai Chen, Shantou (CN)

() Term: 15 Years

(21) Appl. No.: 29/887,762

(22) Filed: Mar. 24, 2023

(30) Foreign Application Priority Data

Mar. 14, 2023 (CN) 202330115756.0

(51) LOC (14) Cl. 03-01

(52) U.S. Cl.

USPC D3/271.1; D3/294; D3/901; D21/483; D28/79
